UNITED STATES PATENT OFFICE.

CHARLES SELKIRK, OF ALBANY, NEW YORK, ASSIGNOR TO THE EMBOSSED COMPANY, OF SAME PLACE.

DESIGN FOR DOMINOS.

SPECIFICATION forming part of Design No. 15,745, dated January 20, 1885.

Application filed July 31, 1884. Term of patent 14 years.

To all whom it may concern:

Be it known that I, CHARLES SELKIRK, a citizen of the United States, residing at Albany, in the county of Albany and State of New York, have invented and produced a Design for Ornamentation of Face Sides of Dominos, of which the following is a specification, reference being had to the accompanying drawings, forming part thereof, in which—

Figure 1 is a view of the face side of a one and two spot domino, and illustrating the ornamentation of the same. Fig. 2 is a view of the face side of a three and four spot domino, and illustrating the ornamentation of the same. Fig. 3 is a view of the face side of a five and six spot domino, and illustrating the ornamentation of the same.

The leading features of my new design for dominos consist in dissimilar and contrasting ornamentations of the different denominational spot-fields, and of ornamentations of spot-fields in which each spot forms an integral part of spot-field ornament, and of combining with each spot and body of the ornamentation of the field a line which encircles the spot and has connection with the body of the field ornamentation by means of stem-lines.

In the drawings, A represents the dominos, and A', A², A³, A⁴, A⁵, and A⁶ respectively represent an ornamented or decorated denominational spot-field.

My new design of ornamentation of the respective denominational fields A' A² A³ A⁴ A⁵ A⁶ are of the style of surface-decoration known as "arabesques," and are fully illustrated in the several figures, which show each spot in each field as forming an integral part of the ornamentation of the field, and also show a circular line, c, bounding each spot, and connected by a stem-line with the branching or scrolling lines of the field's ornamentation.

In field A' the single spot a is shown to be central in the field, with the scrolling-line ornamentation a' extended radially outward in all directions from the circular line c, bounding said spot, as shown.

In field A² the two spots a are shown to be at opposite corners of the field and relatively on a diagonal line, and bordered each by a

circular line, c, and these circular lines c are connected to the body of the ornamentation a' by means of branching stem-lines running inwardly, but in opposite directions on curved lines to the main diagonally-arranged stem-lines of the scroll-form ornamentation occupying the field between the said spots, as shown.

In field A³ the three spots a are shown to be on a line which is relatively diagonal across the field, and bordered each by a circular line, c. The middle spot, a, is shown to be central within the field, and the scroll-form ornamentation a' incloses said middle spot and separates it from the others, and curved stem-lines connect the circular lines c of the respective spots with the scroll ornamentation a' relatively between the corner spots, as shown.

In field A⁴ the four spots a are shown to be arranged at the points of a square and bordered each with a circular line, c. From one of these circular lines spring the lines of the scroll-ornamentation a', which fills the space of the field between the spots. The other circular lines c are connected by stem-lines with branches of the scroll-ornament of the field, as shown.

In field A⁵ the five spots a are shown to be each bordered by a circular line, c, with four of them arranged at the corners of a square, and the other central within the square. The scrolling ornament a' is displayed around the circular line c of the central spot, and fills in the field between this central circular line and the circular lines bordering the corner spots, and the respective circular lines c are connected by stem-lines with this scrolling ornament a', as shown.

In field A⁶ the six spots a are shown to be arranged in that field in two rows of three spots each, and are each bordered by a circular line, c. Arranged between the rows of circular lines c in the spot-field is the scroll-form ornamentation a', with which the circular lines c are connected by curved stem-lines, as shown. B is a border ornamentation, extended continuously around the domino, so as to inclose both spot-fields on the same. This border ornamentation has the appearance of being composed of a series of beads. These beads may be either plain or ornamental in appearance, as may be preferred, and may be

employed in any number so long as they relieve the border margin of the domino from appearance of plainness. C is a division ornamentation, which is arranged at the middle of 5 length of the domino, and across the same between the neighboring spot-fields which they separate. This border ornamentation B forms a pleasing contrast with the background of the spot-fields which they inclose, and also presents to the eye a pleasing contrast with the 10 ornamentations of the respective fields, while at the same time the division ornamentation C presents a pleasing contrast with the differing ornamentations of the spot-fields they 15 separate, and also with the border ornamentation with which this division ornament connects.

I claim—

1. The design for dominos herein shown

and described, the same consisting of an ornamental figure decorating the denominational spot-field, and composed of a series of connected scroll-form members, and the circular line c bordering each spot, and connected by a stem-form line to the ornamental figure, substantially as shown. 20

2. The design for dominos herein shown and described, the same consisting of the ornamental figures decorating the denominational spot-fields, and circular lines bordering 25 each spot, and connected to the ornamental figures by stem-form lines of the border ornamentation B, substantially as shown.

CHARLES SELKIRK.
